[57] CLAIM

The ornamental design for a canopy for pick-up truck bed, as shown and described.

DESCRIPTION

FIG. 1 is a perspective view of a canopy for pick-up truck bed showing my new design, it being understood that the broken lines are for illustrative purposes only; FIG. 2 is a view in side elevation thereof to an enlarged scale;

FIG. 3 is a top plan view thereof to an enlarged scale; FIG. 4 is a view in rear elevation thereof to an enlarged scale;

FIG. 5 is a view in front elevation thereof to an enlarged scale; and

FIG. 6 is a bottom plan view thereof to an enlarged scale.
